UNITED STATES PATENT OFFICE.

OSCAR RICHARD KUEHNE, OF TOPEKA, KANSAS.

VENTILATOR-SMOKESTACK.

SPECIFICATION forming part of Letters Patent No. 410,113, dated August 27, 1889.

Application filed March 26, 1889. Serial No. 304,768. (No model.)

To all whom it may concern:

Be it known that I, OSCAR RICHARD KUEHNE, a citizen of the United States, and a resident of Topeka, in the county of Shawnee and State of Kansas, have invented certain new and useful Improvements in Ventilator-Smokestacks; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of this invention, and is a vertical section. Fig. 2 is partly a side view and partly a sectional view; the section being taken where the broken line xx is shown on Fig. 3. Fig. 3 20 is a horizontal section taken where the broken line zz is shown on Fig. 2.

This invention has relation to ventilator-smokestacks; and it consists in the construction and novel combination of devices, as 25 hereinafter set forth, and pointed out in the appended claim.

In the accompanying drawings, the letter A designates the main pipe of the stack, which is provided with a downwardly-flaring base 30 B, designed to fit upon the top of the smoke-opening of a locomotive or upon a chimney.

C represents a surrounding cylinder-jacket, which is parallel to the main smoke-pipe A, and is connected thereto. Between the main 35 pipe A and cylinder C is an annular passage D, which is entirely open at its lower end, and at its upper end is provided with openings aa into the chamber E above the main pipe, said chamber having about double the 40 sectional area of that of the main pipe, and being bounded by the upper portion of the cylinder-wall, which is extended upward beyond the level of the top of the main pipe for this purpose. The lower end of the cylinder C is provided with an outwardly-curved flange b , which is above the slope c of the base B, and forms therewith an annular mouth or entrance to the annular passage D. The upper end of the cylinder is provided 45 with a downwardly and outwardly inclined flange F, below which are formed a series of openings g in the wall of the cylinder, said

openings having tongues h extending inwardly and upwardly from their lower margins.

55 K are conical mouths having ellipsoidal margins l , connected at their lower ends to the lower flange of the cylinder C. These cone-mouths are arranged in series around the cylinder C and below its upper flange F. Openings m are made at the inner ends or 60 apices of these cone-mouths, leading into the enlargement or chamber E, and extending inward from the cylinder-wall just below these openings are the connections L, which support the cylinder from the main pipe.

Above the cylinder, and separated therefrom by an interval, as at N, is the cap V, in the form of a flattened cone, supported by the rods c' from the cylinder-wall. A central opening d is made in said cap, this opening having a reversely-curved flange or guard l , extending upward and outward and forming the wall thereof, as shown.

The object of the invention is to provide a 75 stack wherein wind-currents entering will assist the draft, and which is so guarded that such wind-currents cannot materially interfere with its office to conduct away the smoke and other products of combustion. The central opening in the cap provides a direct escape for the smoke. When wind is eddying around the stack, the curved flange of said opening directs the wind upward and forming a draft. This flange also prevents the 80 wind from blowing across the surface of the cap in a sheer manner.

The conical passages or mouths K act in a powerful manner to effect an upward draft within the upper chamber of the stack on account of their form, causing the air-currents to converge and enter through the inlets m in a forcible manner.

The annular passage between the cylinder C and the main pipe receives the wind 95 through the lower annular mouth above the base and conveys it upward through the openings aa into the chamber E. This chamber, being larger in sectional area than the main pipe, serves as a sort of reservoir 100 for the smoke to turn in when the wind is flanging on the top of the cap, so that it escapes by the annular opening N below the cap. Wind entering between the ellipsoidal-

formed mouths is directed upwardly into the chamber E, through the opening g and their tongues h, by the inclined annular flange F at the upper end of the cylinder C.

5 By this construction it is designed to provide for controlling the operation of wind-currents upon the stack, so that they shall conduce to a strong upward-draft action within the chamber E and avoid choking the main pipe and fire-box with smoke.

Having described this invention, what I claim, and desire to secure by Letters Patent, is—

10 A smokestack consisting of the main pipe having a flaring base, and an outer parallel cylinder having top and bottom flanges and

forming an annular passage around said main pipe, and an enlarged chamber E above it, ellipsoidal-formed mouths connected to said chamber, the inclined tongues of the cylinder below its upper flange bent inward to form openings, and the cap supported above the cylinder and having a central opening provided with a curved guard-flange, substantially as specified. 25

In testimony whereof I affix my signature in presence of two witnesses.

OSCAR RICHARD KUEHNE.
